PHILIP CHALLIS, OF VICTORIA, LONDON, ENGLAND.

SPARK PLUG.

Application filed February 27, 1922, Serial No. 539,539, and in Great Britain March 17, 1921.

- This invention relates to spark plugs for internal combustion engines, and consists in a novel and simplified construction of plug, which while affording a reduction in the 5 number of constituent parts employed gives improved results in working, renders the flame of the explosion visible and is readily taken apart so that every piece can be easily cleaned and reassembled or replaced.
- 10 Means are also provided for adjusting the width of the gap between the discharge points and for cooling the central electrode to prevent overheating, the maximum cooling effect for the central electrode being afforded 15 by allowing lateral access of air thereto through the plug-barrel.
- The invention is hereafter described with reference to the accompanying drawings, in which:—
- 20 Figure 1 is an elevation and Figure 2 is a longitudinal section of the plug, according to the preferred construction.
- Figure 3 is a cross-section on line 3—3 of 25 Figure 2.
- Figure 4 is a detail section, corresponding to Figure 2 and showing an alternative form of support for the outer end of the electrode.
- Figures 5 and 6, 7 and 8; 9 and 10, and 30 11 12, show various arrangements for adjusting the gap at the spark electrodes.
- The plug-barrel *a* has the usual screw-threaded extremity *a'* carrying or providing the outer electrode in suitable relation to 35 the central insulated electrode *g*. The plug is bored out at its end *a'* to receive an insulator *b* made preferably of silica or quartz and of comparatively short length; this insulator has a conical shoulder *b'* approximately 40 midway of its length, fitting upon a correspondingly oblique seating *a''* in the plug-body, the two conical surfaces providing a gas-tight joint, for example by being ground or otherwise accurately finished, 45 without requiring packing washers. The head *g'* of the central electrode and the lower end of the insulator *b'* also engage each other on a similar but reversed-angle 50 conical seating. The angle of the conical surfaces is preferably such as will ensure that the insulator will be self-freeing from any crushing strain or tendency to chipping or flaking, due to contraction or expansion of the central electrode or of the plug-barrel.
- 55 Thus in the example shown, these faces have an angle of 45 degrees, which allows the insulator to seat itself freely under longitudinal movement while yet allowing it to return when the central electrode stem or head contracts and when the circumferential shrinkage of the plug-body reduces the diameter of the seating in relation to that of the insulator. Any "breathing" movements or differences in expansion and contraction during working of the plug are fully met 60 in this way without danger of crushing the insulator, as would occur in the case of a similar insulator having a conical shape of finer taper.
- The outer end of the plug-body is formed 65 as a thin tubular extension *b''* which encloses an air-space, and the walls of this tubular portion are drilled or apertured as at *b''* to reduce the mass and facilitate the circulation of air laterally into or from said 70 space. The usual hexagon *c* for manipulation may be provided at any convenient position upon the plug-body.
- At the outer end of the plug, the upper 75 insulator *d* rests upon a supporting gallery *e*, the tubular portion *b''* of the plug being counterbored to provide a shoulder *b''* on which gallery is supported.
- The central electrode consists of a metal 80 rod *g* screw-threaded at one end and provided at the other with a flat or mushroom head *g'* which rests by means of a reversed conical seating upon the lower surface of the silica insulator *b*, and is knurled or toothed around its periphery *g''* so as to afford multiple spark-gaps between said head and the 85 extremity of the screw-threaded shank *a'*.
- The stem of the central electrode passes 90 through an axial hole in the silica insulator *b*, is exposed to the air-space within the tubular portion *b''*, and then enters an axial hole in the upper insulator *d*, above which it is fitted (see Figure 2) with a spring-washer *g''*, lock-nut *g''* and terminal nut *g''*. Alternatively a spring gallery may be employed, as shown in Figure 4, consisting of a dished spring washer *e'*, the elasticity of 95 which compensates for the expansion or contraction of all the parts of the plug; thus in this construction the spring washer *g''* and lock nut *g''* are not required.
- To increase its radiating surface, the exposed length of the central electrode stem is preferably formed with a screw-thread, which may be a continuation of that at its 100 outer end. Alternatively the stem may be fitted with other radiating means. I have

shown for example a cooling vane h made of aluminum screwed around the stem, this vane having wings h' to increase the radiating surface. The wings can, with advantage, be arranged to project radially of the plug towards the rectangular windows b^3 in the barrel of the plug. As the addition of the vane h to the central electrode reduces its distance from the tubular extension b^2 10 of the plug-body, I fit a liner f , preferably of mica, with openings f' registering with but of smaller area than the apertures marked b^3 in the plug-body. This insulating liner may be held in position by the 15 downturned periphery of the gallery e , as shown in Figure 2.

Apertures e^2 may be provided to allow air-circulation to or from the air-space. Since the upper insulator is freely exposed to the 20 air for cooling and since the heat is dissipated from both the central electrode stem and the plug-barrel before reaching the points where these parts make contact with the outer insulator, the temperature of the 25 latter never attains a high figure. Thus it is feasible to employ even material such as vulcanized fibre for this insulator, though other insulating materials, such as steatite, porcelain and bakelite will be preferable.

30 Similarly as the tubular portion of the plug-body is so amply cooled by the air circulation through its apertured sides, the hexagon at its upper end remains comparatively cool and it is possible to handle the 35 plug without hurt, even when freshly removed from a working cylinder.

It will be noted that the only joints subject to working pressure are the conical seatings between the intermediate shoulder of 40 the silica insulator and the plug-body and between the lower end of the silica insulator and the central electrode head. Since these can be formed as ground joints without packing material, the plug may be repeatedly taken to pieces for cleaning or replacement of components without prejudice to its gas-tightness when reassembled. Moreover, the low temperature at which the central and outer parts are maintained reduces 45 the amount of expansion and contraction, so that the detrimental consequences of such movements in other plugs are suppressed, while at the same time the design of the parts enables them better to withstand the 55 movement. The spring washer or its equivalent mounted upon the electrode stem serves to tension or load the latter in an elastic manner and allow for all expansion and contraction that may occur in every part in 60 any direction.

Since the head g' of the central electrode rests or beds upon the lower surface or outer end of the silica insulator, by means of a reversed conical seating, as already stated, 65 under the tension of the spring, the central

electrode and the insulator form a pair of spring-loaded valves, co-axial with one another and constantly maintained closed; the insulator and the central electrode head being both coned where they contact with 70 their seatings, a self-centering effect is secured to provide an even width of spark-gap between the central electrode head and the outer electrode or plug-barrel.

According to one method of adjusting the 75 gap, see Figures 5 to 8, the mouth of the plug-shank is fitted with a ring j of nickel or other suitable metal having its inner periphery shaped with a series of cams or spiral curves j' ; the periphery of the central electrode head is formed either with an equal number of lugs or projections i (Figures 5 and 6) or (as in Figures 7 and 8) with a series of cams i' corresponding in pitch with those of the ring. By partially 80 rotating the central electrode, the sparking distance between the outer electrode and the projections i or cam faces i' may be varied between limits determined by the rise of the spirals. The nickel ring may be secured to 85 the plug-shank by being fitted in a counter-bore j^2 of depth slightly greater than the thickness of the ring, the overhanging wall being then turned down, beaded or spun over the ring to secure the latter in position. 90

In another construction, shown in Figures 9 and 10, the head g' of the central electrode carries a plurality of radial arms or lugs i , the lip of the plug-shank having corresponding projections or castellations j^3 ; 100 the gap between the two sets of projections can thus be adjusted by partly rotating the central electrode.

Figures 11 and 12 illustrate another modification in which a ring j^4 of nickel or the like is pressed into an annular groove j^5 in the interior of the shank a' , the section of the groove being either curved or rectangular as shown at the two sides of the shank respectively in Figure 12. The ring is provided with arms j^6 extending parallel to the axis in suitable relation to the central electrode head g' . 110

An important result obtained by the use 115 of a silica insulator and by the open construction of the outer portion of the plug, is that the electrical discharge at the plug electrodes and the flame of the explosion can easily be seen through the apertures. This enables the plugs to be checked by mere inspection when misfiring is suspected, and also enables carburetor and other adjustments to be made by an unskilled operator since the results of the adjustments are immediately visible by the change in colour of the explosion flame. Further the provision of the serrated or knurled head of the central electrode results in oil which may be thrown on the said head sinking into the 120 spaces between the adjacent teeth without 125

necessarily increasing the diameter of the knurled or serrated head and thereby provoking short circuits.

What I claim is:—

- 5 1. A spark-plug, comprising a tubular body, one end of said body being adapted for connection to an engine cylinder and bored to provide a seating; an insulator seated within the bored end of said body, an electrode passing through said insulator; a second insulator surrounding the stem of said electrode, said stem being exposed between the adjacent edges of said insulators, an apertured support for said second insulator, said support resting upon said body; said tubular body being apertured to allow access of air to the exposed length of said electrode within said body and between said insulators; said support being apertured to
- 10
- 15

allow passage of air from within said body and means for holding the parts in position.

2. A spark-plug, comprising a tubular body; a hollow insulator made of silica mounted in said body; an electrode passing through said insulator and having its head mounted thereon; a second insulator surrounding the stem of said electrode; an apertured support for said second insulator, said support resting upon said body, the apertures in said support being so placed as to allow observation therethrough of illumination transmitted through said silica insulator; and means for holding the parts in position.

In testimony whereof I hereunto affix my signature.

PHILIP CHALLIS.
